UNITED STATES PATENT OFFICE

WILLIAM RAY PARMELE, OF PORTLAND, OREGON

WING CONSTRUCTION FOR AEROPLANES

Application filed December 11, 1928. Serial No. 325,205.

The primary purpose and object of my device is to impart additional stability to a heavier than air flying machine during the initial stages of flight.

5 A further object of my invention is to impart a greater lifting capacity to the heavier than air flying machine during the initial or starting flight, and to provide means for the air ship attaining greater speeds after the 10 machine has risen sufficiently from earth to make higher speeds possible.

A further object of my device consists in providing a wing structure, the upper surface of which may be changed to meet the 15 flying necessity whether it be for sustaining greater loads or maintaining greater speeds, or for stabilizing the plane when coming to repose after the flight.

It is well known in aeronautics that the 20 depth of the aerofoil relative to its cross sectional length determines the stability and speed that the ship may attain per unit of power used.

It is also well known that the ship having 25 the aerofoil having greatest loading surface, depth of wing, has greatest stability in initial flight and that the wing structure of minimum depth of wing, has greatest speed possibilities. It is therefore desirable to provide 30 means for regulating the depth during flight to adapt the wing to the load and speed requirements and to make such changes during actual flight.

A further object of my invention relies in 35 a construction that is adapted to regulating the depth of the wing structure and to uniformly increase or decrease the depth of the leading portion of the wing from the wing tip to the central portion of the wing to meet 40 the conditions of flight that are actually met during flight. The device being adapted for manipulation during actual flight.

A still further object of my invention 45 relies in a structure that is adapted to being stream lined irrespective of the depth of the wing and to uniformly increase in depth from the top to the central portion, or to uniformly decrease in depth from the central 50 portion outward, and to make changes if

increase and decrease of depth during actual flight.

With these and incidental objects in view, the invention consists of certain novel features of construction and combination of parts, the essential elements of which are set forth in the appended claims, and a preferred form of embodiment of which is hereinafter shown with reference to the drawings which accompany and form a part of this 60 specification.

In the drawings:

Fig. 1 is a front view of an aeroplane, the full lines of the aerofoil representing my new and improved device repressed for rapid 65 economical flight, and the dotted lines illustrating the aerofoil with the top wing surface distended for initial flight, and for carrying a maximum load both at starting and in full flight at maximum speed.

70 Fig. 2 is a cross section view, taken on line 2—2 of Fig. 1 looking in the direction indicated with the aerofoil in normal position.

75 Fig. 3 is a cross section view, taken on line 2—2 of Fig. 1 looking in the direction indicated, with the aerofoil in position for initial flight or landing.

Fig. 4 is a longitudinal, sectional view, of the aerofoil, taken on line 4—4 of Fig. 3, 80 looking in the direction indicated.

Fig. 5 is a top, plan view, of the aerofoil.

Fig. 6 is a fragmentary, sectional view of the link structure, disposed within the aerofoil, to illustrate in detail the connection 85 of the link elements.

Like reference characters refer to like parts throughout the several views.

1 is the fuselage of a heavier than air flying machine, the aerofoil is shown at 2, the 90 spars illustrated at 3 and 4, and the rib sections shown at 5. The upper skin of the aerofoil is divided into a plurality of longitudinal strip sections 6, 7 and 8, shown in Figs. 2 and 3. The section shown at 8, is 95 permanent and fixedly secured to the supporting structure. The sections 6 and 7 are secured to the adjustable ribs 9 and 10. The front end of adjustable rib section 9 is hingedly secured to the rib 5, by any suitable 100

means, as by a journal pin 11, the skin portion of the adjustable rib over-lapping, as shown at 12, to prevent the admission of air within the wing structure. It is important that there be maintained a close fitting connection to prevent the building up of air pressure within the wing. The rear portion of the rib 10, carries a projecting pin 13, that is slidably disposed within the slot 14, disposed within the main rib portion 5, of the wing. The free ends of the adjustable ribs 9 and 10, are hingedly secured at 15, and journaled within a suitable bearing of the supporting strut 16. The supporting strut 16 is hingedly mounted, relative to the supporting journal 17, associated with the lower or bottom end of the strut 16. The strut 16 is composed of two links 18 and 19, illustrated in repressed position, in Fig. 2 and secured together and hingedly held in place at their meeting ends by the pin 20. The pin 20 is also journaled relative to one end of the connecting link 21. The connecting link 21 is secured on its oppositely disposed end to the crank arm 22, by any suitable means, as by a journal pin 23. The crank arm is fixedly mounted upon the shaft 24. The shaft 24 is disposed longitudinally of the aerofoil which is divided into a plurality of compartments, each compartment carrying individual skin elements that coact with adjacent skin elements in order that they may be actuated in unison by the partial rotation of the shaft 24 to which each of the actuating crank arms 22 are mounted. The rotation, or partial rotation of the shaft 24 by hand or power manipulation of the actuating lever 25 actuates the associated elements, their movement in one direction extends or increases the depth of the wing and their movements in the oppositely disposed direction represses the associate elements and lessens the depth of the wing surfaces. In preferred embodiment, the link elements 18 and 19 uniformly increase in length from the tip of the wing to the center portion in order that a uniformly tapering wing may be developed that will be of cross sectional area, increasing or decreasing in depth to or from the central portion of the aerofoil structure, as illustrated in Fig. 4. When the wing is in the initial position or flight, either in starting or landing the upper surface of the wing is distended, as shown in detail in Fig. 3, in which position the stability of the flying machine is greatly increased. When full flight is obtained, the upper structure may be gradually repressed until the flying machine is placed in position for rapid economical flight. The wing structure is illustrated in detail in Fig. 2.

While the form of mechanism herein shown and described is admirably adapted to fulfill the objects primarily stated, it is to be understood that it is not intended to con-

fine the invention to the one form of embodiment herein shown and described, as it is susceptible of embodiment in various forms, all coming within the scope of the claims which follow.

What I claim is:

1. In a device of the class described, the combination in the wing structure of an aeroplane, of primary ribs, superposed secondary ribs, one end of each secondary rib being hingedly disposed at the leading end of the primary rib and the oppositely disposed end of each secondary rib being slidably disposed relative to the primary rib, said secondary rib being comprised of sectional members hingedly connected, a metallic skin covering for the upper surface of the wing and directly supported by the secondary rib, a strut composed of links hingedly secured together and to the secondary rib elements for raising and lowering the secondary rib and means for manipulating the link strut.

2. In an aeroplane wing construction, in combination, a rigid lower supporting surface, primary rigid ribs transversely disposed thereon, an adjustable upper skin supporting surface having secondary adjustable ribs disposed therebelow and superposed on the primary ribs, said secondary ribs comprising a plurality of sectional members hingedly connected with each other and with the actuating means, said secondary ribs hingedly secured and overlapping the leading portion of the primary ribs and slidably secured to and overlapping the rearward portion of the primary ribs, actuating means comprising of links hingedly secured to secondary ribs on their one end and to crank arms on their other end, said crank arms fixedly mounted on a shaft extending longitudinally of the wing structure and actuated by rotating a lever connected with the main shaft.

3. In an aeroplane wing construction, in combination, a plurality of rigid primary ribs in spaced relation forming a plurality of compartments within the wing structure, adjustable secondary ribs comprised of a plurality of sections hingedly secured to each other and to the primary ribs and with the actuating means, said secondary ribs hingedly secured to and overlapping the leading portion of the primary ribs and slidably secured to and overlapping the rearward portion of the primary ribs, a strut comprising links hingedly secured together and to the secondary rib elements, and means for actuating the link strut.

4. In a device of the class described, comprising an aeroplane wing structure having an adjustable upper cover supporting surface, a shaft longitudinally disposed within the wing and moveably journaled thereto, a plurality of struts in spaced relation with the primary ribs and their lower ends hingedly journaled thereto, the upper ends of said

struts being hingedly secured to the meeting ends of the secondary rib sections, said struts comprised of links hingedly journaled with each other and with connecting links, said connecting links hingedly journaled to crank arms fixedly mounted upon the shaft, and operating means connected with the shaft and with a lever stationed in the central control quarters.

5. In a device of the class described, the combination in the wing structure of an aeroplane, a plurality of primary ribs, a like number of secondary ribs superposed upon the primary ribs in such a manner as to prevent lateral movement of the upper skin supporting surface, said primary and secondary ribs disposed in spaced relationship transversely of the wing forming a plurality of compartments, the secondary ribs being composed
10 of two sections hinged to each other, the free end of one being hinged to and overlapping the leading end of the primary ribs to prevent the entry of air within the wing structure, the free end of the other being slidably
15 disposed relative to the primary rib and overlapping said primary rib to prevent the entrance of air within the wing and to maintain the stream line of the wing, a strut composed of links hingedly secured to each other
20 and to the secondary ribs at the meeting place of the sections, and means for manipulating
25 the link strut.
